GRID OR GRATING

Walter F. Schulz, Youngstown, Ohio, assignor to
Truscon Steel Company, Youngstown, Ohio, a
corporation of Michigan

Application May 26, 1932, Serial No. 613,753

28 Claims. (Cl. 94—30)

The primary object of my invention is to provide a novel combination of special forms of metal, including a special method of welding, and that combines and cooperates with concrete 5 or similar material, to form a flooring supported upon other frame work, and of such construction as to provide a relative maximum of economy in production and installation and of efficiency in use.

10 The structure of the invention may be used with or without the concrete for ceilings or wall structures, with or without separate covering of the open side thereof.

Specifically the use of the structures of my 15 invention for flooring of certain types of bridges will illustrate and exemplify its advantages for employment in various capacities.

Where a structure is designed to carry a superimposed load of the character common on floors 20 of bridges or otherwise and the well-known wrought metal T-bar can be used, reversed as shown in the accompanying drawings, such T-bar provides the most economical method of resisting the stresses of superimposed weight, where 25 properly combined with concrete or similar material. In such use, the horizontal extensions at the bottom of the bar as a reversed T are known as flanges and the vertical central portion as the web. The stresses of superimposed pressure are 30 exerted chiefly in tension at the bottom, decreasing upward toward the neutral axis in the web, at which point compression stresses commence and increase to the top of the web. Of structural shapes of such general type, the most economically produced in a given tonnage of like 35 sectional areas are flats or plates, squares and rounds, next angle bars, next T bars, and most expensively I and H bars or beams. Wrought metal is relatively strong in tension and weak 40 in compression. In the T-bar of wrought metal the angle portion can be rolled to the required predetermined sectional area to furnish the tensile resistance required without undue waste of metal in the web (or in top flanges such as 45 the H-bar) where not required on account of resistance to compression being otherwise provided. In the preferred form of my construction, the compressive resistance is principally provided by concrete or similar relatively inexpensive 50 material strong in resistance to compressive forces and furnishing at its surface a desirable tractive medium for traffic.

The edges of the flanges of T-bars properly formed most advantageously lend themselves to 55 union by economical welding to such extent as

may be required, and the thinner upper edges of the webs to the special welding of the special cross bars hereinafter described.

An embodiment of the invention is illustrated in the accompanying drawings, wherein:

Figure 1 is a plan view of a unit or slab.

Figure 2 is a perspective view showing the same partly filled with concrete.

Figure 3 is a perspective view of the meeting portions of two units showing the relation of 10 the anchoring or tie elements thereof.

Figure 4 is a detail cross sectional view of the parts as shown in Figure 3 when filled with concrete.

Figure 5 is a similar view but taken at a different point.

Figure 6 is a cross sectional view on the line 6—6 of Figure 5.

Figure 7 is a perspective view showing the use of angle bars instead of T-bars, holes for bolting, 20 riveting, or plug welding to unite the structure to a metallic supporting framing, and the filled V form of cross bars welded into the tops of the webs so as to be flush with the surface thereof.

Figure 8 shows the use of plates instead of T 25 or angle bars.

Figure 9 is a detail sectional view showing how an angle bar may be employed for completing the outermost side of the structure.

In my preferred form of construction the desired number of T-bars of the desired length and dimensions are assembled side by side in the shop with the flanges 1 constituting the base of the structure and with webs 3 upstanding in spaced parallel relation. The abutting edges of 35 the flanges of each section are welded either continuously or at spaced intervals, as shown at 9, with or without staggering, as may be determined with reference to the stresses to be met, and so as to thereby unify the action of the flanges. De- 40 pending upon the area to be covered the structure may be completely fabricated in the shop, but usually it is preferable to produce the same in units or sections to be assembled on the job. Such a unit or section is shown in Figure 1. 45

Where economy of fabrication is justified with reference to requirements, angle bars 1a may be employed instead of T-bars, and where T-bars are employed, an angle bar of proper width in the horizontal angle may be used to close an outer 50 channel of the structure after the sections have been assembled to the requisite width of the flooring or roadway as indicated at 7b in Figure 9.

Where only grating or open flooring is required, and tensile strength at the bottom of the struc- 55

ture does not necessitate the use of T-bars or angle bars, plates 1c may be used.

To unite the T-bar, angle-bar or plate sections at the top and provide, with the top of the webs, 5 metallic protection against the breaking down of the concrete surface of the floor or roadway and against slipping or skidding upon the surface, cross-bars 10 are provided. The cross-bars 10 are preferably of approximate filled-V section, 10 preferably slightly blunted at the tip and of shape in section approximately as best shown. Using an approximate filled-V section for welding to the thinner vertical webs 1, 1a or 1c, the heat of well-known resistance welding, diffused 15 over the surfaces of the cross-bars, is concentrated at the point of the V and causes the metal of the web first to melt at such point of contact. Under continued application of heat and pressure, the metal of the web and cross-bar is progressively 20 melted along lines corresponding to the downward sides of the V until the V-bar is brought to a point where its upper surface conforms substantially to the upper edge of the web, and complete welding of the V-bar to the web occurs at 25 all points of contact. As a further result, the surfaces of the metal conform substantially to the surfaces of the concrete when poured and the roughness incident to other methods of welding other forms of cross-bars is avoided. This welding 30 process is more fully explained in my Letters Patent No. 1,973,113, dated September 11, 1934.

In the production of the grid or grating it will be noted that one set of alternate bars projects beyond one outer side web 8 and is downturned to 35 form anchor hooks 11, while the bars between said hooks terminate at the said web. These latter bars, however, extend beyond the opposite side of the unit and are correspondingly formed with hooks. Preferably also openings 12 are 40 formed in the meeting edges of certain of the flanges 1, these openings being provided for means used to fasten the structure to an underlying supporting frame.

The units or slabs as shown in Figure 1, are 45 preferably fabricated at the factory and may be of predetermined standard lengths or made of special size for the particular place where they are to be used. If desired they may be either flat or crowned.

50 The sections of my structure constituting, with the concrete or like material, the floor or roadway, are supported upon spaced portions of the main framing structure, one of which is indicated at 12a. They are held firmly united to the framing structure and against longitudinal movement under tensional strain by bolting, riveting or welding through holes 13. I prefer welding by the process known as plug welding through such holes. But any form of welding may be employed. By 55 this form of construction I provide by the flanges, where required, and by the part of the web below the neutral axis, and to the extent required, the maximum of tensional resistance with a minimum of expense in a structure of this type.

60 The channels can then be filled in with concrete. As a matter of fact the grid or grating will itself support traffic and machinery for laying the concrete. In other words concrete mixers or trucks carrying the concrete can pass freely thereover. 65 The concrete is filled into the channels until flush with the upper edges of the webs 8 and cross bars 10, as shown at 14 in Figures 2, 4, 5, and 6. When so filled in a complete floor, deck or roadway is provided in which the concrete is in the form of 70 continuous elongated bars anchored down by the 75

cross bars 10, the upper edges of the webs 8 and cross bars serving as a non-skid surface and directly resisting the abrasive action of the traffic on the concrete. Moreover as the cross bars taper downwardly they overlie the margins of the concrete on opposite sides of the same, providing chamfered corners at the top that prevent the spalling of the concrete under traffic. Furthermore it will be obvious by a comparison of Figures 3, 4, and 5 that the concrete between adjacent units serves as a tie in which the hooks 11 are embedded, thus creating an effective joint between adjacent units. At the same time the projecting hooks 11 extending substantially to the unprojecting ends of the cross bars of the adjacent units provide substantial continuity of the metal surface throughout the area.

From a structural standpoint the concrete or similar material, cooperating with the portion of the web above the neutral axis, provides the compressive resistance required. Moreover by the use of the form of cross bars and the method of welding above described, the tops of the webs are united and form a grid not only cooperating with the concrete in producing traffic cohesion without having any protruding surfaces, but also without weakening the web in resistance to the negative bending moment, the latter as next explained.

While the principal stresses under superimposed loads are those of compression and tension between the points of support of the spans as above stated, normally greatest under a load at the center of the span, there is a change into a negative bending moment, a reversal of such 35 stresses, at and adjacent to the points of support of such a structure upon the main framing. If the webs were cut at their tops for the insertion of cross bars or members, it would weaken the webs through lack of continuity at the points of 40 tensional stress of the negative bending moment. By the present method of construction and welding applicable to the preferred form of cross bars, continuity of the upper portion of the webs is 45 maintained and the full strength thereof in tension maintained even though the surface of the cross members is brought flush with the top of the web.

By sufficient welding between adjoining edges of the flanges of the T-bars or the edges of angle-bars to adjoining sides of angle-bars, resistance to tensional stress transversely of the length of the T-bars is provided, and the bottom part of the structure becomes in substantial effect a plate extending throughout the entire lower area, resisting all torsional stresses as well as longitudinal and transverse tensional stresses. The concrete or like material, cooperating with the intervening webs, resists transverse as well as longitudinal compressive stresses. The cross-bars resist tensional stress in any transverse negative bending moment.

From the foregoing, it is thought that the construction, operation and many advantages of the herein described invention will be apparent to 65 those skilled in the art without further description, and it will be understood that various changes in the size, shape, proportion and minor details of construction may be resorted to without departing from the spirit or sacrificing any of the 70 advantages of the invention.

What I claim is:

1. In a wrought metal structure of the type described, a set of flanged bars with the flange of one bar substantially abutting the flange of the 75

- adjacent bar, and means uniting the said abutting flanges of the bars to adjacent flanges to provide in the flange portions of the bars required tensional resistance in angular directions.
5. 2. In a wrought metal structure of the type described, T-bars located side by side with the opposite flanges of one substantially abutting the flanges of the bars on opposite sides thereof, and means uniting the said abutting edges of the flanges thereof, to provide in the flange portions of said T-bars required tensional resistance in angular directions.
10. 3. A structure as described in claim 1 combined with a filler to provide additional resistance to compression strains.
15. 4. A structure as described in claim 2 combined with a filler to provide additional resistance to compression strains.
20. 5. A structure as described in claim 1 combined with cross bars connecting the tops of the webs of the flanged bars.
25. 6. A structure as described in claim 2 combined with cross bars connecting the tops of the webs of the T-bars.
30. 7. In a wrought metal structure of the type described, a series of supporting bars located side by side providing spaced webs, and cross bars connecting the tops of the webs and press welded into said tops with their upper faces substantially flush with the top edges of the webs.
35. 8. A structure as described in claim 7 in which the cross bars are substantially V-shaped in cross section.
35. 9. A structure as described in claim 7, and in which the lower edges of the supporting bars are united and a filling of cementitious material is located between the webs to provide additional resistance to compression stresses.
40. 10. A structure as described in claims 7 and 8 and in which the lower edges of the supporting bars are united and a filling of cementitious material is located between the webs to provide additional resistance to compression stresses.
45. 11. A wrought metal structure of the type described comprising a series of inverted T-bars located side by side and having the edges of their adjacent flanges united to resist transverse tension strains, and cross bars connecting the tops of the webs of said united T-bars.
50. 12. A wrought metal structure of the type described, comprising a series of inverted T-bars located side by side and having the edges of their adjacent flanges united to resist transverse tension strains, cross bars connecting the tops of the webs of said united T-bars, and filling in the spaces between the webs of the T-bars and acting to resist compression strains transmitted to the said webs.
60. 13. A wrought metal structure of the type described comprising a series of inverted T-bars located side by side and having the edges of their adjacent flanges united to resist transverse tension strains, cross bars of substantially V-shape in cross section connecting the tops of the webs of said T-bars and press welded into the same with their flat top faces substantially flush with the top edges of the webs, and cementitious filling in the spaces between the webs of the T-bars and acting to resist compression strains transmitted to the said webs.
70. 14. A grid or grating unit comprising a series of supporting bars located side by side, and a set of cross bars set into the supporting bars and having means at their ends lying alongside the outside adjacent supporting bar for tying to an adjoining grid or grating.
75. 15. A grid or grating unit comprising a series of supporting bars located side by side, and a set of cross bars set into the supporting bars and having projecting ends provided with anchoring means lying alongside the outside adjacent supporting bar for tying to an adjoining grid or grating.
10. 16. A grid or grating unit comprising a series of supporting bars located side by side, and a set of cross bars set into the supporting bars and having projecting ends provided with offset anchoring hooks that extend alongside the outermost supporting bar.
15. 17. A grid or grating unit comprising a series of supporting bars located side by side, and a set of cross bars set into the supporting bars, certain of the bars projecting on one side of the unit, and other bars projecting on the opposite side of the unit.
20. 18. A grid or grating unit comprising a series of supporting bars located side by side, and a set of cross bars set into the supporting bars, certain of the bars projecting on one side of the unit and other bars projecting on the opposite side of the unit, the projecting ends of the bars of one unit being adapted to substantially align with non-projecting ends of the bars of an associated unit.
25. 19. A grid or grating unit comprising a series of supporting bars located side by side, and a set of cross bars set into the supporting bars, certain of the bars projecting on one side of the unit and other bars projecting on the opposite side of the bars being provided with anchoring means.
30. 20. A grid or grating unit comprising a series of supporting bars located side by side, and a set of cross bars set into the supporting bars, certain of the bars projecting on one side of the unit and other bars projecting on the opposite side of the unit, said projecting portions of the bars being provided with offset anchoring hooks.
35. 21. A plurality of grid or grating units located side by side, each unit comprising supporting bars located side by side, cross bars carried by the supporting bars, the cross bars of one unit at one side of the same aligning with certain of the cross bars of the adjacent unit and lapping other cross bars of the adjacent unit.
40. 22. A plurality of grid or grating units located side by side, each unit comprising supporting bars located side by side, cross bars carried by the supporting bars, the cross bars of one unit at one side of the same aligning with certain cross bars of the adjacent unit and lapping other cross bars of the adjacent unit, and means for tying the lapped ends together.
45. 23. A plurality of grid or grating units located side by side, each unit comprising supporting bars located side by side, cross bars carried by the supporting bars, and alternately disposed cross bars projecting respectively on opposite sides of the unit, the projecting portions of the cross bars of one unit extending between the projecting portions of certain cross bars of an adjacent unit and in substantial line with other of said cross bars.
50. 24. A plurality of grid or grating units located side by side, each unit comprising supporting bars located side by side, cross bars carried by the supporting bars, alternately disposed cross bars projecting respectively on opposite sides of the unit, the projecting portions of the cross bars of one unit extending in substantial line with 75

certain cross bars of an adjacent unit and between the projecting portions of other of said cross bars of such adjacent unit, and means for tying together said interposed cross bar portions.

5 25. A plurality of grid or grating units located side by side, each unit comprising supporting bars located side by side, cross bars carried by the supporting bars, the cross bars of one unit at one side of the same lapping the cross bars of the adjacent unit and said lapped portions having offset anchoring hooks that lie between the outermost supporting bars of said adjacent units.

10 26. A plurality of grid or grating units located side by side, each unit comprising supporting bars located side by side, cross bars carried by the supporting bars, and alternately disposed cross bars projecting respectively on opposite sides of the unit, the projecting portions of the cross bars of one unit extending between the projecting portions of an adjacent unit and said interposed projecting portions having offset anchoring hooks that lie between the outermost supporting bars of said adjacent units.

15 27. A plurality of grid or grating units located side by side, each unit comprising supporting bars located side by side, cross bars carried by

the supporting bars, and alternately disposed cross bars projecting respectively on opposite sides of the unit, the projecting portions of the cross bars of one unit extending between the projecting portions of an adjacent unit, said interposed projecting portions having offset anchoring hooks that lie between the outermost supporting bars of said adjacent units, and a cementitious binder between the units and in which the hooks are embedded.

20 28. A plurality of grid or grating units located side by side and each comprising flanged supporting bars placed side by side to form a substantially closed base and spaced upstanding webs that produce open-topped channels, cross bars 15 substantially V-shape in cross section embedded and welded in the free margins of the webs with their outer faces substantially flush therewith; said bars alternately projecting beyond the side webs and being formed into downturned anchoring hooks, the hooks of one unit alternating with those of the next adjacent, and cementitious material filling the channels and extending beneath the cross bars and having the hooks embedded therein, thereby forming a tie between adjoining 25 units.

WALTER F. SCHULZ.
